R. H. ANDERSON.
PORTABLE FOLDING BED.
APPLICATION FILED APR. 11, 1912.

Patented Mar. 3, 1914.

Fig. 1.

UNITED STATES PATENT OFFICE.

ROBERT H. ANDERSON, OF SAN DIEGO, CALIFORNIA, ASSIGNOR TO RUTH B. ANDERSON, OF SAN DIEGO, CALIFORNIA.

PORTABLE FOLDING BED.

1,089,370.

Specification of Letters Patent.

Patented Mar. 3, 1914.

Application filed April 11, 1912. Serial No. 639,994.

To all whom it may concern:

Be it known that I, ROBERT H. ANDERSON, a citizen of the United States, and a resident of San Diego, in the county of San Diego and State of California, have invented certain new and useful Improvements in Portable Folding Beds, of which the following is a specification.

My invention relates to beds mounted on rollers and adapted to be moved at will from one part of a house to another part, and more particularly into and out of a closet or narrow room and the objects of my invention are, first, to provide a bed which 15 may be readily moved into and out of a closet or narrow room, without difficulty in guiding the same, second, to provide such a bed that may be readily changed to provide means for moving it to any position in any 20 room or into other rooms through narrow doorways, third, to provide such a bed that is simple, durable and easily constructed, fourth, to provide such a bed that may be folded into a narrow compact form.

With these and other objects in view as will appear, my invention consists of certain novel features of construction, combination and arrangement of parts as will be hereinafter described in detail and particularly set forth in the appended claims, reference being had to the accompanying drawings and to the characters of reference thereon, which form a part of this specification, in which:—

Figure 1. is a rear elevational view of my bed in its folded position, Fig. 2. is a side elevational view thereof, and Fig. 3. is a perspective view of the carriage portion of my bed showing the shifting means for 40 changing the bed to different locations in a room or from one room into another.

Similar characters of reference refer to similar parts throughout the several views.

The rollers 1, axles 2, 8 and 9, longitudinal supports 3, head frame 4, supporting frame 5, bed frame 6 and foot frame 7 constitute the principal parts of my bed construction. The rollers 1 are preferably of a broad base and composed of wood and may be covered 50 with a cushion material if desired so as not to mar the floor upon which the bed is moved. These rollers are revolvably mounted in pairs upon the axles 2, 8 and 9 and the preferable construction is three of these sets 55 of rollers as shown best in Fig. 3. Upon the

axles 2 and 9 are rigidly mounted the longitudinal supports 3,—one on the outside of the rollers 1, so as to provide a broad base within a minimum of space for the bed when folded. These supports are preferably made 60 of angle iron and are each provided with a reinforcing piece 3^b. On the middle axle 8 are provided two cams 8^a which are rigidly mounted thereon and adapted to engage with the lower surfaces of the horizontal 65 members of the supports 3. This axle 8 is mounted in the vertical members of these supports in slotted holes 3^a adapted to allow this axle to move vertically therein, and it is provided with a lever 2^a adapted to facilitate its partial rotation in said supports, and when it is rotated in a certain direction it will lower the two middle rollers relatively to the end ones, thus allowing the bed and frame to be pivoted or tilted on these 70 two middle rollers, thus allowing a ready shifting of the bed in different directions. One of the supports 3 is provided with steps 3^c adapted to regulate the movement of the lever 2^a. In the upper surface of this support 3 is also provided an adjustable bolt 3^d adapted for a central rest or support for the head of the bed when in its folded position. Upon this outer support 3 is rigidly mounted the head frame 4 of the bed, and on the 80 inner longitudinal support are rigidly mounted the bed frame supports 5, which connect to the head frame by means of horizontal pieces 5^a and connections 4^a. Pivotally mounted on the supports 5 at points 5^b 85 is the bed frame 6. The head end portion of this frame is made of metal and of a sufficient weight to more than balance the remainder of the frame, so that when the mattress and bed clothing are placed thereon in 90 their proper position, the bed will approximately balance at the pivot points 5^b. The foot frame 7 is connected to the bed frame by means of double links 7^a and 7^b, so that when the bed is in the folded position as 95 shown in Fig. 2, it assumes the position requiring the minimum of space, and which may be readily placed in its proper position when the bed frame is let down for use.

Though I have shown and described a 100 particular construction and arrangement of parts, I do not wish to be limited to this particular construction and arrangement, but desire to include in the purview of my invention, the construction and arrangement 105 110

- substantially as set forth in the appended claims. It is obvious that with this construction, when the bed is folded up as shown in Fig. 2, it assumes a very narrow and compact form; that this bed may be rolled into or out of a very narrow closet or room without being guided as long as all of the rollers are on the same level; that by shifting the lever 2^a into a position so that the cams force the axle 8 downward the horizontal supports will allow the bed to be supported on the central axle, thus allowing either end to be tilted up and the bed shifted around to any position desired; that the bed is simple of construction, strong and durable and may be placed in a very narrow closet, and that the broad metallic head portion of the frame gives rigidity to the frame throughout.
- Having thus described my invention, what I claim as new and desire to secure by Letters Patent is:-
1. The combination with the head frame of a portable folding bed of two parallel, horizontal base members rigidly mounted on the lower ends of the supports of said head frame, three pairs of rollers mounted on said horizontal base members,—one pair being located at each end thereof and the third pair located near the middle of said base members, and a means in connection with said middle pair of rollers for raising it relatively to the other pairs of rollers.
  2. In combination with the head frame of a portable folding bed, two parallel,

horizontal base members rigidly mounted on the lower ends of the supports of said head frame, a bed frame pivotally mounted practically in equilibrium in said head frame, two parallel horizontal base members rigidly mounted on the lower extended ends of said head frame supports, a plurality of pairs of rollers mounted in said horizontal base members, the one pair thereof being located near the middle of said base members, and a means in connection with said middle pair of rollers adapted for raising and lowering it relatively to the other pairs of rollers.

3. In a portable folding bed, the combination of a head frame provided with a plurality of extended support members, two parallel horizontal base members rigidly mounted on the ends of said extended support members, a bed frame pivotally mounted in said head frame adapted to be in equilibrium therein, a plurality of pairs of rollers mounted on said horizontal base members, the pair near the middle thereof being adapted to be raised and lowered relatively to the other pairs, and a lever means adapted to facilitate the raising and lowering thereof.

In testimony whereof, I have hereunto subscribed my name in the presence of two subscribing witnesses.

ROBERT H. ANDERSON.
